UNITED STATES PATENT OFFICE

2,216,195

TELEPHONE SECRETARY

Garniss W. Hunter, Columbus, Ohio

Application September 13, 1938, Serial No. 229,789

2 Claims. (Cl. 312—188)

My invention, which relates more particularly to telephone-secretaries of the types disclosed in Letters Patent No. 1,969,305 and No. 1,969,306, issued August 7, 1934, No. 1,996,767, issued April 9, 1935, No. 1,997,585, issued April 16, 1935, No. 2,000,957, issued May 14, 1935, and No. 2,015,679, issued October 1, 1935 has for an object to provide certain new and useful improvements designed to render the operations of the parts more automatic and to facilitate the use of the secretary.

It is an object of the invention to provide the secretary with a plurality of telephone directory-carriers (especially useful in large cities where several directories are used) so arranged and constructed that when not in use they remain within the confines of the secretary and do not project over the open (horizontal) door, but which may easily be brought forward and held in a position so as to be easily readable and may be properly illuminated by the light (see Pat. No. 1,969,306 and No. 1,996,767 supra) of the secretary.

Other objects will in part be obvious and in part be pointed out hereinafter.

To the attainment of the above objects and ends the invention still further resides in those novel features of construction, combination and arrangement of parts, all of which will be first fully described in the detailed description and then be particularly pointed out in the appended claims, reference being had to the accompanying drawings, in which:

Fig. 1 is a front elevation of the secretary (parts of the supports being broken away), with the door open.

Fig. 2 is an enlarged section on the line 2—2 of Fig. 1.

Fig. 3 is a further enlarged detail section of one of the directory receiving sections of the secretary.

Fig. 4 is a detail section on the line 4—4 of Fig. 3.

Fig. 5 is an enlarged detail section later again referred to.

Fig. 6 is a section on the line 6—6 of Fig. 1.

Fig. 7 is an enlarged detail section showing the hinge connection between the door and the memo-pad carrier.

Referring now to the accompanying drawings, in which like numerals and letters of reference indicate like parts in all the figures, 1 represents the base of the secretary, 2 the outer side-walls, 4 the back wall, 7 the intermediate or side walls

of the directory section, 22 the top wall, and 25 the door which is hinged at 26 to the base 1.

The directory section of the secretary is divided by suitable partitions to provide receptacles for the directories and the slides on which they are mounted. The directory section may be provided with a sufficient number of horizontal partitions dividing it into horizontal recesses or receptacles, one above the other, to contain the desired number of directories (one to each receptacle), or it may be provided with rearwardly-downwardly inclined partitions to form inclined receptacles one above the other, or it may be provided with a set of pivoted and stepped directory-carriers which swing on horizontal axes from an inclined downwardly-forward position in use to an upwardly-rearwardly inclined position when not in use; or a combination of all such means may be embodied in the same structure, as illustrated in the accompanying drawings.

In the illustrated embodiment the top receptacle of the directory section is formed by the horizontal partitions 3 and 16 between which the directory-carrying slide or tray 17 is located.

In order to hold the directory in position for use, in which position it will be adequately illuminated by the light 21, the partition 3 has a notch 19 and the slide 17 has a notch 18 so formed that when the rear end of the slide 17 is placed in notch 19, the front end of the partition 16 will lie in notch 18 and the directory 15 and slide 17 will stay in the inclined position (shown in Fig. 5 in full lines and in dotted lines in Fig. 2) by its own weight.

Below the partition 16 is a series of downwardly, rearwardly inclined transverse partitions 5, defining between them receptacles for directories. In order that the user need not pull out the directories at the steep angle of the partitions 5, means are provided whereby as the user pulls out a directory its angle of inclination with respect to the horizontal is reduced. This is accomplished by providing in each receptacle a supplemental partition 6 which is hinged or pivoted at its rear end at 13 and has its sides located in recesses 8 in the intermediate side-walls 7 (see Figs. 2, 3 and 4), the recesses 8 being so formed that the front edge of the partition 6 can be lowered to the partition 5 beneath, thus making the plane of the partition or shelf 6 approach the horizontal. The partitions 6 may have side flanges 9 slotted as at 10, to receive the guide pins 11 of the directory-carrying slides 12, the structure being such that when a slide 12 has been pulled out it may be swung down (see dotted

lines Fig. 2 and full lines Fig. 3) to a forwardly inclined position to be properly illuminated by the light 21 and be held in readable position by resting on the projecting edge of the partition 5 beneath, or on some other suitable part below. Springs 14 of sufficient power to hold the partition or shelf 6 up are provided as shown.

The fronts 45 of the slides 12 may have aprons 46 to constitute closures for the fronts of the receptacles between the partition 6 and the partition 5 next below (see Fig. 2).

The directories 15 are secured to their respective slides in any approved manner. As the specific means for securing the directories to the slides is no part of the present invention, the same has not been illustrated in the drawings.

The illuminating means (light 21 and reflector 20) may be of the construction shown in Patent No. 1,996,767 supra, and per se is not of the present invention. The usual top front cleat 23 is provided to aid in supporting the reflector 20.

The directory carriers 24 are pivoted at 39 to the walls 7, and are arranged in stepped formation so that when they are swung down to their positions of use (see dotted lines, Fig. 2) they will each lie in proper position for illumination by light 21.

By reference to Fig. 1 it will be seen that the walls 7 are spaced from the walls 2 to define two end compartments one of which provides a receptacle for the telephone T and the other a receptacle for the memo pad, etc. In the telephone receptacle is located an inclined cleat 31 fixed to the base 1, on which rests the rear edge 38 of a telephone stand 29 (see Fig. 2). This stand 29 is hinged at 28 to a fixed cleat 27 on the door 25, the structure of cleats 27, 31 being such that the stand 29 remains substantially horizontal in all positions, i. e., with the door open, with the door closed, or with the door in transit, thus making it unnecessary to fasten the telephone to its stand and leaving the instrument free to be removed from the stand if and when desired.

The memo-pad, etc., are secured to a base 32 which is hinged at 33 to the door 25 (see Figs. 6 and 7) and is provided with a rocker-cleat 34 which, when the door is open, holds the base 32 at the proper angle to present the pad M to the user in a position most convenient for use. The base 32 may be provided with front and rear stop cleats 35 to hold the pad M in place when the pad is not otherwise secured to the base 32.

The space between walls 7 and 2 at the memo-pad side may be further partitioned, as at 36, 37, to provide pigeon-holes and at 38 to provide a space for a drawer 39. Likewise the space between walls 2 and 7 at the telephone side may be divided by partitions 42, 41, 43 to form pigeon-holes and a space for a drawer 40.

The door 25 may be held in the open position by the usual brace 44 (see Figs. 1 and 6).

From the foregoing it will be seen that with the door in the closed position the telephone T and

memo-pad M will be back in their respective compartments and the several directories will be out of sight. When the door is swung open the telephone and the pad will be automatically moved out to usable positions. By pulling out the desired directory slide or slides, the directories are brought into position for illumination and use.

In this application I lay no claim to the telephone stand and to the memorandum directory carrier as they will constitute the subject matter of divisional applications.

While I have illustrated and described the preferred embodiment of the invention, it will of course be understood that changes in the details of construction, design and proportion of parts may readily be made by those skilled in the art without departing from the invention and within the scope of the appended claims.

What I claim is:

1. A cabinet having a base, side walls, a back wall, a top wall, and a drop door hinged to the base to serve as a closure for the cabinet or as a forward extension to the base accordingly as said door is in one position or another, vertically spaced downwardly and rearwardly inclined transverse fixed partitions in said cabinet defining a directory receptacle, an intermediate partition hinged at the rear on a horizontal axis within said receptacle, a directory-carrying slide cooperatively slidably mounted on said intermediate partition, means connecting said slide to said intermediate partition slidably and pivotally in order that when said slide is pulled out it may be swung to a forwardly-downwardly inclined position, and yieldable means continuously acting to hold said intermediate partition elevated when the slide is in but yieldable to permit lowering said intermediate partition in pulling out the slide.

2. A cabinet having a base, side walls, a back wall, a top wall, and a drop door hinged to the base to serve as a closure for the cabinet or as a forward extension to the base accordingly as said door is in one position or another, vertically spaced downwardly and rearwardly inclined transverse fixed partitions in said cabinet defining a directory receptacle, an intermediate partition hinged at the rear on a horizontal axis within said receptacle, a directory-carrying slide cooperatively slidably mounted on said intermediate partition, means for connecting said slide to said intermediate partition slidably and pivotally in order that when said slide is pulled out it may be swung to a forwardly-downwardly inclined position, and yieldable means continuously acting to hold said intermediate partition elevated when the slide is in but yieldable to permit lowering said intermediate partition in pulling out the slide, said slide having a front closure wall for the front of said directory receptacle when the slide is in.

GARNISS W. HUNTER.
